UNITED STATES PATENT OFFICE.

LUTHER F. SEELAR, OF ST. LOUIS, MISSOURI, ASSIGNOR TO ST. LOUIS CAR COMPANY,
OF ST. LOUIS, MISSOURI, A CORPORATION OF MISSOURI.

SPRING-MOUNTING FOR CAR-TRUCKS.

1,331,529.

Specification of Letters Patent. Patented Feb. 24, 1920.

Application filed December 6, 1919. Serial No. 343,036.

To all whom it may concern:

Be it known that I, LUTHER F. SEELAR, a citizen of the United States, residing at St. Louis, State of Missouri, have invented 5 certain new and useful Improvements in Spring-Mountings for Car-Trucks, of which the following is a specification.

This invention relates to spring mountings for car trucks.

10 An important object of the invention is to provide means whereby rebound of the car body due to the recoil of the springs is cushioned by the springs themselves.

15 A further object is to provide a novel and efficient means for securing the spring butts to the truck frame.

Other objects and advantages will be apparent throughout the course of the following description.

20 In the accompanying drawings wherein for the purpose of illustration is shown a preferred embodiment of my invention.

Figure 1 is a side elevation of a portion of a truck showing the spring mounting 25 thereof.

Fig. 2 is a plan view of the spring mounting shown partly in section.

Fig. 3 is a section taken on the line 3—3 of Fig. 1.

30 Fig. 4 is a perspective view showing the attachment of the spring butts to the truck frame, and

Fig. 5 is a fragmentary perspective of the outer or free end of the spring.

35 Referring now more particularly to the drawings, the numeral 10 indicates a truck frame provided upon its end with a lower longitudinally extending portion 11 forming a spring support. Above the spring 40 support 11 is an upper longitudinally extending portion of the frame 12 forming an overhanging shoulder. Between the overhanging shoulder 12 and the inner end of the spring support 11 is formed a notch 45 against which a portion of the springs abut.

A leaf spring 13 is provided having the ends of the leaves notched as at 14 to form spaced sections 14'. The truck frame 10 is received between the spaced portions 14'.

A spring band or yoke 15 is provided having an aperture which receives the ends of the spring adjacent the cut out portions thereof. This yoke is provided in its upper and lower faces with notches 15 which receive the truck frame 10 within the notch 55 thereof.

The bottom 16 of the yoke 15 is provided with downwardly extending flanges 17 which are secured to the longitudinally extending support 11 of the truck frame by 60 means of bolts 18 or the like, the base or bottom 16 of the yoke resting upon the upper surface thereof. It will be seen that movement of the spring's leaves transversely of the frame 10 is provided against by the 65 interlocking engagement of the springs themselves with the frame and also the engagement of the yoke therewith. Vertical displacement of the springs is prevented by the shoulder 12 and the yoke. 70

The outer end of the spring or that portion of the leaves which extends the full length thereof is provided with a longitudinally elongated aperture 19. Secured to supports 20 forming a portion of the body 75 frame of the car as by means of bolts 21 is a tubular casting 22 having the lower end thereof open as at 23. Slidably mounted within the tubular casting 22 is the second tubular casting 24. A spring 25 is disposed 80 intermediate the lower end 26 of the tubular casting 24 and the upper end 27 of the tubular casting 22. The tubular casting 22 is provided with downwardly extending ears 28 having mounted therein a transverse bolt 85 29. A bolt 30 is mounted in apertures formed in the bottom 26 of the tubular casting 24 and the top 27 of the tubular casting 22 and is provided upon its upper end with a nut 31. The lower end of the bolt 90 30 extends through the aperture 19 of the spring 13 and is provided in its lower end with a longitudinally elongated slot 32 adapted to receive the transverse bolt 29.

In normal operation the castings 22 and 24 95 and spring 13 maintain the position in which they are illustrated in Figs. 1 and 3. If, however, an unusual jar is applied the spring

25 is compressed and the spring 13 distorted. This action is caused by the spring 13 pressing against the bottom 26 of the casting 24 and forcing it upwardly. The elongated slot 19 of the spring prevents undue thrust being placed upon the castings 22 and 24 and also prevents the shock from being imparted to the car frame in a longitudinal direction. In the rebound action resulting from the compression of the spring 25 and the distortion of the spring 13 the outer end of the spring engages the transverse bolt 29 and the spring 13 accordingly cushions such rebound.

15 As many changes are possible in the shape, size, and arrangement, of the various parts shown and described, I do not limit myself to the specific structure herein set forth, but may make any such changes, without departing from the spirit of the invention, or the scope of the subjoined claims.

What I claim is:

1. The combination with a truck frame, of a leaf spring having the butt ends of its leaves notched, to receive the truck frame and means for securing said spring to said frame.

2. The combination with a truck frame, of a leaf spring provided in the butt ends of the leaves thereof with notches receiving the truck frame, and a yoke receiving said spring adjacent the butt end thereof and provided upon one side thereof with flanges receiving a portion of said frame.

3. The combination with a truck frame provided in its end with a notch, of a leaf spring having its butt end disposed within the notch of the frame said butt end provided with a notch receiving the frame at the inner end of the notch thereof, and means for securing said spring to said frame.

4. The combination with a truck frame provided in its end with a notch, of a leaf spring having its butt end disposed within the notch of the frame, said butt end being provided with a notch receiving the frame at the inner end of the notch thereof, and means for securing said spring to said frame, comprising a yoke receiving said spring adjacent the butt end thereof and provided with downwardly extending flanges receiving said frame at the bottom of said notch.

5. The combination with a truck frame provided upon its end with a lower longitudinally extending portion forming a spring support and an upper longitudinally extended portion forming an overhanging shoulder, of a leaf spring provided in its butt end with a notch adapted to receive the frame intermediate said spring support and said overhanging shoulder, a yoke receiving the spring adjacent the butt end thereof and provided with notches receiving the frame intermediate said shoulder

and said spring support, and downwardly extending flanges formed upon said yoke and engaging the sides of the spring support and secured thereto.

6. The combination with a truck frame provided upon its end with a lower longitudinally extending portion forming a spring support and an upper longitudinally extended portion forming an overhanging shoulder, of a leaf spring provided in its butt end with a notch adapted to receive the frame intermediate said spring support and said overhanging shoulder, a yoke receiving the spring adjacent the butt end thereof and provided with notches receiving the frame intermediate said shoulder and said spring support, and downwardly extending flanges formed upon said yoke engaging the sides of the spring support and secured thereto and bolts extending through said flanges and said spring support said shoulder engaging the upper side of said yoke.

7. The combination with a car body and a truck frame, of a spring having one end secured to the truck frame and an opening formed in the free end thereof, a cylindrical member having an open lower end secured to said car body, a second cylindrical member having its upper end open slidably within said first named cylindrical member, a compression spring disposed intermediate said cylindrical members, depending ears formed on said second cylindrical member, a member connecting said ears and a member secured to said first named cylindrical member and said connecting member and extending through the opening of said spring.

8. The combination with a car body and a truck frame, of a spring having one end secured to the truck frame and an elongated opening formed in the free end thereof, a cylindrical member having an open lower end secured to said car body, a second cylindrical member having its upper end open slidably within said first named cylindrical member, a compression spring disposed intermediate said cylindrical members, depending ears formed on said second cylindrical member, a member secured to said first named cylindrical member and said connecting member and extending through the opening of said spring intermediate said connecting member and the bottom of said second cylindrical member.

9. The combination with a car body and a truck frame, of a cylindrical member having an open lower end secured to said car body, a second cylindrical member having its upper end open slidably mounted within said first named cylindrical member, a compression spring disposed intermediate said cylindrical member, pending ears formed on said second cylindrical member, a transverse member connecting said ears, a bolt extend-

ing through axial openings formed in said cylindrical member and provided upon its upper end with a nut, an elongated slot formed in the lower end of said bolt and receiving said transverse member a spring provided in one end with a longitudinally elongated slot adapted to receive said bolt intermediate the bottom of said second cylindrical member and said transverse mem- ber, and means rigidly connecting the other 10 end of said spring and said truck frame.

In testimony whereof I affix my signature in presence of two witnesses.

LUTHER F. SEELAR.
